UNITED STATES PATENT OFFICE.

ARTHUR J. LEWIS, OF STRATFORD, CONNECTICUT.

SLIDE BUCKLE.

1,425,396.

Specification of Letters Patent. Patented Aug. 8, 1922.

Application filed April 3, 1922. Serial No. 548,898.

To all whom it may concern:

Be it known that I, ARTHUR J. LEWIS, a citizen of the United States, residing at Stratford, county of Fairfield, State of Connecticut, have invented an Improvement 5 in Slide Buckles, of which the following is a specification.

This invention relates to buckles and especially to that type of buckle known as slide 10 buckles used for adjusting the length of straps, webbing, and the like, such as suspenders, and is so constructed as to secure the strap in adjusted lengths without penetrating the material, and no stitching is required in attaching the buckle to the strap. 15

It is an object of the invention to provide a buckle of this type which will securely hold the strap and not slip in operation when a strain is applied thereto, which is 20 simple in construction comprising a single piece of wire, and which will be flat and have no projecting portions to catch on articles of clothing or other elements when in use. 25

With these and other objects in view I have devised the improved buckle disclosed in the accompanying drawing, in which

Fig. 1 is a plan view of the end portion of a suspender with the buckle in position.

Fig. 2 is a longitudinal, central section 30 through the strap and buckle, as shown in Fig. 1.

Fig. 3 is a top plan view of the buckle detached.

Fig. 4 is an end view looking from the left of Fig. 3, and

Fig. 5 is an end view looking from the right of Fig. 3.

The strap 10 may be of any suitable material and is shown with its free end looped through the eye of a button-loop 11, and the body of the strap and the free end thereof are reeved through the buckle 12 in the manner shown in Figs. 1 and 2.

Buckle 12 is preferably made of a single 45 piece of square wire as shown, although round wire or other material may be employed, if desired. The square wire, however, has a somewhat better holding effect due to the comparatively sharp corners.

The midlength of the wire is bent downwardly or offset, as shown at 13, a distance substantially equal to the thickness of the wire. The ends of the wire are then bent 50 at right angles, as shown at 14, forming spaced parallel side members 15. The ends

are then bent at right angles toward each other at 16 and then again at right angles to form the two immediate bars 17 closely adjacent each other and having their free ends within the curve of the offset 13. It will be noted that the side members 15 and intermediate bars 17 are all in the same plane. In fact, the whole buckle is in substantially a single plane with the exception 65 of the offset portion 13 and it, therefore, takes up very little room and has no projecting parts to catch on articles of clothing, and the like, when in use. This construction also gives two loops free at one 70 end connected at the other end by the bar having the offset 13.

The body of the strap 10 extends under the outer bars 15 through the loops and over the intermediate bars 17, as shown in 75 Figs. 1 and 2, forming bends or bights therein which prevent sliding of the buckle under strain. The free end of the strap, after passing through the buckle 11, is extended upwardly intermediate the bars 17, bent 80 upon itself around one of said bars beneath the body of the strap and under the adjacent side member 15. This member is securely held by the body of the strap and the intermediate bars under strain so that 85 no stitching of the free end to the body is required and no sewing operation is necessary, thus decreasing the cost of assembling. When strain is applied to the button-loop 11, the resulting pressing downwardly of 90 the central bight 18 of the body member will grip the free end 19 more tightly between this bight and the intermediate bar 17 about which the strap is wrapped increasing the holding effect, and, pressing of the 95 two bars 17 against the inclined walls 20 of the offset 13, will also tend to move the free ends of these bars together to more tightly grip the end of the strap.

It will be apparent this construction is 100 very simple and, therefore, may be easily and cheaply manufactured. As all the side and intermediate bars are in a single plane, the buckle is flat and has no projecting elements. Also that, through the peculiar construction pointed out, the strap is securely held with no liability of slipping under strain but still may be easily adjusted when required.

Having thus set forth the nature of my 110 invention, what I claim is:

1. A slide buckle including a pair of loops

having side bars connected at one end and free at the opposite ends, intermediate bars extending from the free ends to and over the connecting member, the side and intermediate bars being in substantially the same plane, and the connecting member having its central portion offset laterally from said plane.

2. A slide buckle including a pair of loops having side bars connected at one end and free at the opposite ends which extend inwardly to form intermediate bars having their free ends extending over the connecting member, the side and intermediate bars being in substantially the same plane, the said connecting member being curved laterally from said plane between the side members, and the free ends of the intermediate members contacting the inclined walls of said connecting member.

3. A slide buckle comprising spaced substantially parallel side bars and intermediate bars between the said side bars and in

substantially the same plane therewith; one end of the side bars being connected with one end of the adjacent intermediate bars, and the other ends of the side bars being connected by a member having a portion thereof offset laterally from the plane of the bars and at one side of the free ends of the intermediate bars.

4. A slide buckle comprising a single length of wire bent at right angles on opposite sides of its midlength to form substantially parallel spaced side bars, the free ends being then bent toward each other and then at right angles to form intermediate bars between, substantially parallel with and in substantially the same plane as the side bars, the midlength of the wire between the side bars being offset laterally from the plane of the bars, and the free ends of the intermediate bars extending on the inner side of the offset portion.

In testimony whereof I affix my signature. 45
ARTHUR J. LEWIS.
